LIQUID DISPENSER

Robert C. Old, Spokane, Wash.

Application March 17, 1951, Serial No. 14,533

Term of patent 14 years

(Cl. D58—26)

To all whom it may concern:

Be it known that I, Robert C. Old, a citizen of the United States, residing at Spokane, State of Washington, have invented a new, original, and ornamental Design for a Liquid Dispenser, of which the following is a specification, reference being had to the accompanying drawing, forming a part hereof.

I claim:

The ornamental design for a liquid dispenser, as shown and described.

ROBERT C. OLD.
